[57] CLAIM

The ornamental design for a package condiment holder, substantially as shown and described.

DESCRIPTION

FIG. 1 is a perspective view of the package condiment holder, showing my new design;

FIG. 2 is a top plan view thereof;

FIG. 3 is a bottom plan view thereof;

FIG. 4 is a side elevational view thereof, the view of the opposite side being identical thereto;

FIG. 5 is an end elevational view thereof, the view of the opposite end being identical thereto; and

FIG. 6 is an exploded perspective view thereof.

FIG. 1.FIG. 2.*FIG. 3.*FIG. 4.*FIG. 5.*FIG. 6.
